UNITED STATES PATENT OFFICE.

HENRY C. SCHRADER, OF WHEELING, WEST VIRGINIA.

PUNTING-MACHINE.

SPECIFICATION forming part of Letters Patent No. 398,454, dated February 26, 1889.

Application filed April 19, 1888. Serial No. 271,246. (No model.)

To all whom it may concern:

Be it known that I, HENRY C. SCHRADER, a citizen of the United States, residing at Wheeling, in the county of Ohio, State of 5 West Virginia, have invented certain new and useful Improvements in Punting-Machines, of which the following is a specification, reference being had therein to the accompanying drawings.

10 This invention has relation to a machine for cutting and finishing the bottoms of glasses, and the objects and advantages thereof, together with the novel features, will hereinafter be described, and particularly pointed 15 out in the claims.

Referring to the drawings, Figure 1 is a front elevation of a machine constructed in accordance with my invention. Fig. 2 is a side elevation, and Fig. 3 is a similar view of 20 the opposite side.

Like numerals of reference indicate like parts in all the figures of the drawings.

12 represent two opposite standards of the frame-work, which are mounted upon a suitable base, 3, and are connected at their top 25 and intermediate the same and their base by cross-beams 4 5.

Journalized in opposite bearing, 6, formed in the standards 1 and 2, is a cross-shaft, 7, 30 rigidly mounted upon which are a pulley, 8, a cutting-wheel, 9, and a grinding-wheel, 10. Below the shaft 7 there is located a sand-box, 11, in which is a water tank or basin, 12.

Journalized in vertically-opposite bearings 35 13, formed in the two parallel cross-beams 4 and 5, are vertical shafts 14 and 15, the former being mounted directly over the cutting-wheel 9 and the latter directly over the grinding-wheel 10. Upon the upper end of the 40 shaft 14 is secured a weight-receptacle, 16, or it may be a weight, and at the lower end of said shaft is a glass-receiving head or chuck, 17—in this instance formed of cork. Just above the upper bearing, 13, of the shaft the 45 same is provided with a worm-gear, 18, and intermediate said bearings there is a fixed collar or boss, 19. A lever, 20, mounted upon an arm, 21, terminates under the collar or boss 19, which, when operated through the 50 medium of a chain, 22, and foot-lever 23, serves to raise and lower said shaft.

Above the machine there is suspended—in this instance from a beam, 24—a sand-hopper, 25, provided with a chute designed to deliver sand upon the cutting-wheel 9, the quantity 55 of sand delivered being regulated by a rod, 26, operating a gate, 27.

The upper end of the vertical shaft 15 is swiveled in an eye, 28, from which a rope, 29, extends up over a pulley, 30, mounted on the 60 beam 24, and extends down at the side of the machine. A sleeve, 31, is mounted on the shaft 15 intermediate its bearings, which sleeve is longitudinally slotted, as at 32, to receive a lug, 33, formed on the shaft, so that 65 said shaft may slide vertically in the sleeve and rotate in connection with it. At the upper end of the sleeve is mounted a worm-gear, 34, and at the lower end thereof is a twin-grooved pulley, 35. At the lower end of the 70 shaft is mounted a rubber or other chuck, 36, adapted to receive and retain a tumbler or glass.

Pivoted to the sleeve 31, near its lower end and extending laterally therefrom, are arms 75 37, from which depend rigid arms 38, to the ends of which are pivoted open heads 39, in which are journaled spindles 40, carrying pulleys 41, mounted within the head and terminating in glass-receiving chucks 42—in this 80 instance formed of rubber. An endless belt, 43, is passed around the twin pulley 35 and laterally over twin pulleys 44, mounted on the arms 38, provided with belt-tighteners 45, and down over the pulleys 39, thus transmitting 85 motion from the sleeve 31 to the spindles 40.

The belt-tightener 45 is fastened to the end of the axle of the pulley 44 by means of a tightening-screw, 58. In order to make it operate, it is pressed outward against the belt 90 and fastened in this position by tightening said screw. Any well-known means may be employed for the purpose of holding these arms out in an operative position, however, without departing from the spirit of my invention. 95

Journalized in bearings 46, formed on the cross-bar 4 of the frame-work, is the power-shaft 47, which is provided at its end with a working-pulley, 48, and idle-pulley 49 and 100 with worm-gears 50 and 51, the former meshing with the worm-gear 18 on the shaft 14.

and the latter meshing with the worm-gear 34 of the shaft 15. Power is conveyed to the shaft through any ordinary system of belting leading from a motor, and the shaft 7 is also 5 likewise operated independently in this instance.

At the side of the frame-work described there projects an angular arm, 52, at the end of which is formed a bearing, 53, which, in 10 connection with an opposite and similar bearing, 53^x, formed in the standard 2, forms bearings for a horizontal shaft, 54, which is operated through the medium of a pulley, 55, and carries a polishing-wheel of wood, 56, or other 15 suitable material.

The operation of my invention is as follows: A glass, *a*, is placed upon the chuck 17, and the bottom thereof is suitably cut by the cutting or coarse grinding wheel 9, the weight in 20 the receiver 16 giving the required pressure. By pressing upon the foot-lever 23 the shaft 14 is raised and the glass removed and its place refilled, and the removed glass is placed upon one of the spindles or chucks 42, where- 25 upon the glass is ground. The second glass is then removed from the chuck 17 and placed upon the other chuck, 42, and so on until the chucks 42 are each provided with a glass, and also the chuck 36, the latter being accom- 30 plished by raising the same through the me- dium of the cord or rope 29, the shaft and spindles rotating all the time. As it takes longer to grind than cut, the capacity of the machine for grinding is consequently in- 35 creased by the three chucks 36 and 42. The chucks 42 and 36 are held in contact with the revolving grinding-wheel by gravity and may be swung out and the glasses easily removed therefrom. The rear head, 39, is provided with 40 a forwardly-projecting handle, 57. After the glasses are removed from the spindles of the shaft 15, they are finished upon the polishing- 45 wheel 56. In the operation of cutting, sand flows from the box 25 over the cutting-wheel 9, which greatly facilitates the cutting opera-

tion, the sand then dropping into the recep- tacle 11.

Having described my invention and its op- eration, what I claim is—

1. In a machine of the class described, a 50 grinding-wheel and a vertical rotating shaft bearing a chuck mounted above said wheel, in combination with a sleeve surrounding said shaft and arms attached to said sleeve and provided with glass-receiving chucks, sub- 55 stantially as described.

2. In a machine of the class described, the combination, with a grinding-wheel rotatably mounted upon a shaft, of a shaft mounted for reciprocation in a sleeve and adapted for ro- 60 tation therewith and provided with oppositely-pivoted rotatable spindles having glass-re- ceiving chucks at their ends, substantially as specified.

3. The combination, with the frame-work, 65 of a sleeve longitudinally slotted and carry- ing a gear mounted thereon, a shaft mounted for reciprocation in the sleeve and provided with glass-receiving chucks mounted in spin- 70 dles provided with pulleys, an endless belt 70 mounted over the pulleys and over a pulley mounted on the shaft, and of a power-shaft provided with a gear adapted to mesh with the gear on the sleeve, substantially as specified.

4. The shaft 15, mounted as described, and 75 having pivoted arms 37 and twin pulley 35, the depending arms 38, having pivoted heads 39, carrying spindles 40, provided with pul- 80 leys 41 and chucks 42, the pulleys 44, mounted on the depending arms, and the chuck 36, 85 mounted on the shaft, and the belt 43, mounted as described and adapted to give motion to the chucks, substantially as specified.

In testimony whereof I affix my signature in presence of two witnesses.

HENRY C. SCHRADER.
